UNITED STATES PATENT OFFICE

ALONZO B. ELY AND EDWIN L. HARMON, OF GROTON, NEW YORK, ASSIGNEES TO L. C. SMITH & CORONA TYPEWRITERS INC., OF SYRACUSE, NEW YORK, A CORPORATION OF NEW YORK

TYPEWRITING MACHINE

Application filed May 20, 1929. Serial No. 364,448.

This invention relates to improvements in typewriting machines and has for its principal object to provide a simple and efficient tabulating means for such machines. A further object of the invention is to provide a tabulating mechanism especially applicable to portable three-quarter strike typewriters having a shifting platen carriage, such as the well known "Corona" typewriter. Other objects are to provide a tabulating means for machines of the last mentioned type consisting of few parts and operable from a key in the keyboard of the machine, and to provide tabulating means applicable to the "Corona" machine with a minimum of change. Other objects and advantages will appear from the following description in detail of the preferred embodiment of the invention illustrated in the accompanying drawings, in which:

Fig. 1 is a fragmentary vertical longitudinal sectional view of the machine, many of the parts being omitted to more clearly show the present improvements, the tabulating devices being in normal idle condition;

Fig. 2 a fragmentary perspective view showing the tabulating and associated devices and parts in the same condition as in Fig. 1;

Fig. 3 a fragmentary plan view of the machine looking down perpendicular to the plane of the main flat web of the rearwardly and downwardly tilted carriage bed, part of the carriage being broken away and the tabulating device being shown in normal idle condition;

Fig. 4 a fragmentary vertical longitudinal sectional view showing the tabulator key fully depressed and the carriage arrested by the tabulating means; and

Fig. 5 a detail view showing the adjustable mounting of the stop bar on its supporting brackets.

The improvements are shown embodied in a Corona machine of substantially the construction shown in patent to Avery et al., No. 1,700,828, except that in the present machine the carriage and its bed are of sheet metal construction and the ribbon spools are mounted on the main frame instead of the

carriage bed. Only so much of the machine as is necessary to a full understanding of the present improvements has been shown and will be described.

The sheet metal carriage bed has its bottom plate 10 lying in a rearwardly and downwardly inclined plane and fixed on the upper ends of a pair of raceway members 11 connected by a tie rod 12, these raceway members of the shift frame of the machine (which comprises said members, tie rod and bed) being opposed to a pair of companion stationary raceway members 13 secured to the side walls of the main frame 14 of the machine, and suitable antifriction balls being interposed between the stationary raceway members and shift frame raceway members. Said parts coact to support and guide the sheet metal carriage to shift upwardly and rearwardly in a plane perpendicular to the plane of the flat bottom of the bed when shift key 15 is depressed.

The shift key lever 16 is pivoted at 17 on a lug 18 pendent from the horizontal web 19 of one of a pair of sheet metal brackets 20 secured to the opposite side walls of the main frame by screws 21. A rock shaft 22, journalled in the main frame, has a pair of arms 23 carrying pins 24 connected with the shift frame raceway members 11 to raise and lower the shift frame, and the forked rear end of the shift key lever embraces the pin on one of these arms to rock the shaft and arms to elevate the shift frame from the normal lower case position shown in the drawings to upper case position. The shift key lever is guided in the key lever guide comb 25 of the machine which is secured to the side walls of the main frame by screws 26. Brackets 20 are formed with type rest 90 supporting arms 27 to which the ends of the rest 28 for the type bars 29 are secured.

The sheet metal platen carriage 30 has pendent channel raceway flanges 31 and 32 embracing the upper channel portions of raceway flanges 33 and 34 of the carriage bed, suitable antifriction bearings being confined in the raceways and supporting the carriage to travel transversely of the machine with its bottom part inclined rearward 100

and downward. The carriage is urged from right to left by the usual spring drum (not shown) and its feed is controlled by an escapement constructed substantially as shown in the patent above referred to. This escapement comprises a dog rocker 35 pivoted on the rear ends of arms 36 and 37 of a sheet metal bracket 38, secured to the bottom of the carriage bed, and carrying fixed and loose dogs 39 and 40 coactive alternately with escapement wheel 41 fixed on a shaft journaled in said bracket, which shaft has a pinion 42 fixed on its upper end and meshing with feed rack 43 on the carriage.

The normal position of the escapement is shown in Figs. 1 and 2, and the dog rocker is adapted to be rocked down and up at the key strokes to letter feed the carriage under control of the dogs, and also to be given an excessive downward movement to the position shown in Fig. 4 to free the carriage from control of the escapement, as more fully shown and described in said patent.

The release of the carriage is effected by a releasing bell-crank lever 44 pivoted at 45 on arm 36 of bracket 38, and normally held in the inactive position shown in Figs. 1 and 2 by a spring 55 connecting the upstanding bell crank arm with a lug 46 on said bracket arm. The rearwardly extending arm of the bell crank has a stop lug 47 normally abutting the bottom face of the transverse main body of bracket 38 and is also formed at its rear end with a lateral extension or dog-rocker-depressing lugs 48 extending across the forwardly extending stop arm 49 of the dog rocker which has a stop lug 50 at its forward end also normally abutting the bottom face of the main body of bracket 38. The upstanding arm of the bell-crank 44 extends upward through a clearance opening 56 in the main bottom plate of the carriage bed 10, and its rearwardly extending arm lies under the bed and the main body of bracket 38.

The dog rocker is yieldably held in normal position by its return spring 51 connecting a pendent arm 52 of the rocker with a pendent lug 53 on side arm 37 of escapement bracket 38. The dog rocker is actuated for letter-spacing by the universal bar (not shown) which pushes rearward on pendent arm 54 of the rocker. The machine is provided with a release bail (not shown) pivoted on the carriage and coactive with the notched upper end of the upstanding bellcrank arm to release the carriage from control of the escapement.

So far as above described the parts are all constructed and operate as in the Corona machine as heretofore known. In the machine, as constructed in accordance with the present invention, key-operated means are provided for releasing the carriage and arresting it at predetermined points after jump

movements under pull of the carriage advancing cable and spring drum. Also the brackets 20 are utilized to support the ribbon spools and their pawl and ratchet driving devices, and one of these brackets (that at the left hand side of the machine) is utilized for attachment of parts of the tabulating mechanism.

The carriage 30 in the particular construction shown is made in two sections 58 and 59 adjustably locked together by clamping screws 57 which extend through fore-and-aft slots 60 in the main flat plate-like portion of the rear section 59 and are screwed into threaded holes in the main flat plate-like portion of the front section 58, the bottom of the carriage comprising two flat overlapped plates clamped together by said screws. At each end of the carriage is arranged a group of preferably three of these clamping screws 85 in a preferably triangular grouping as shown, the screws of each such group extending through fore-and-aft extending slots 61 in the forward end of one of a pair of fore and aft extending flat sheet metal bars or brackets 62 for supporting a notched tabulator stop bar 63. The rear ends of brackets 62 are bent downward and abut the rear face of stop bar 63 to support the stop bar 63 in rear of flange 34 of the carriage bed in a plane between the planes of the bottoms of the carriage and bed, a pair of clamping screws 64 extending through a pair of horizontal transversely extending slots 65 in the downturned end of each bracket and being screwed into threaded holes in the stop bar, as more clearly shown in Fig. 5.

The stop bar is thus very rigidly held to the carriage, but is adjustable at either or both ends relatively to the carriage fore-and-aft of the machine and is also longitudinally adjustable transversely of the machine for insuring proper coaction between the variably settable column stops 66 on the bar and the key-settable counterstop 67 on the shift frame of the machine. The bar 63 and the tabulator or adjustable column stops 66 are of ordinary construction, the stops being removable and lockable in any desired notches in the bar, and as many of them employed as may be desired to determine the desired columnar positions of arrest of the carriage.

The non-traveling counterstop 67 comprises a fore and aft extending sheet metal bar lying loosely flatwise on the upper face of the flat bottom plate of the carriage bed with its rear end extending through a horizontal slot 68 formed in the rear raceway flange 34 of the bed below the raceway channel of the flange and preferably flush at its lower edge with the upper face of the bed bottom. The walls of the slot restrain lateral and up and down movements of the stop 67. Said stop is formed with a nose 69 at its rear end normally forward of the path of travel 130

- of stops 66 and adapted to be projected into the path of travel of that portion of each stop which extends down in front of column stop bar 63.
- 5 Stop 67 is formed with opposite parallel longitudinal edge portions 70 and 71 coactive with the ends of slot 68 to guide the rear part of the stop in its projecting and retracting movements, and with a transverse stop shoulder 72 at the forward end of edge portion 71 adapted to abut the front face of race-way flange 34 (as shown in Fig. 4) to limit the extent of rearward projection of the stop with nose 69 in position to be struck by a traveling stop 66. Guide edge 71 coacts with the adjacent end wall of slot 68 to hold the stop 67 against swinging to the left beyond a predetermined position with relation to the carriage bed when struck by a traveling stop,
- 10 the stop 67 being pivotally held at its forward end by a rivet 73 to the slightly upwardly offset inner end of a two-arm sub-lever 74, the main portion of which lies flatwise on the upper face of the carriage bed between the
- 15 raceways. The upwardly offset inner end of sub-lever 74 is provided at its rear edge with a finger 99 extending transversely of the machine with its free end in front of the up-standing arm of escapement releasing bell-
- 20 crank lever 44, said finger being bendable fore and aft for adjustment to insure proper actuation of the releasing bell-crank by the tabulating mechanism. Sub-lever 74 is pivotally held intermediate its ends to the bed
- 25 by a shouldered pivot screw 75 and the outer arm of said lever is formed with a pendent lug 76 extending down through a clearance opening 77 in the carriage bed adjacent the left hand side of the machine.
- 30 A wire link 78, permanently bendable for purposes of adjustment as indicated in the drawings, connects the lower end of said lug 76 on the sub-lever with the upper end of the upwardly and rearwardly extending arm 79 of the tabulator key lever 80. The key lever arm 79 is pivotally held at its lower end by a pivot screw 81 to the slightly inwardly offset lower end portion 82 of the vertical web of the left hand bracket 20, which web, as heretofore described, is clamped against the inner face of the left hand side wall of the main frame by screws 21. The main key carrying arm of the tabulator key lever 80 extends forward from arm 79 about mid length of arm
- 35 79 under the horizontal part 19 of said bracket 20 between the shift key lever and the main frame side wall and has its upstanding key supporting front end guided in a slot 83 in a horizontal part of the guide comb 25.
- 40 The tabulator key lever is normally held returned by a return spring 84 connected at its lower end with the main forwardly extending arm of the lever and having its upper end hooked over the transversely extending por-
- 45 27 of the left hand bracket 20. A laterally bent stop lug 85 on the upstanding key-stem portion of key lever 80 abuts the under face of the horizontal portion of comb 25 which has the key lever guide slot 83 to limit the return movement of the key lever 80 and parts connected therewith, including stop 67. A laterally bent stop lug 86 on said stem portion is adapted to arrest depression of the tabulator key after shoulder 72 on stop 67 strikes flange 34 to prevent accidental bending of the adjustable wire link 78.
- 50 Each of the brackets 20 in the present construction is formed with three arms 87 for supporting a plate 88 to which is attached the cover 89 for one of the ink-ribbon spools of the machine. The spool is mounted on the upper end of the hub 91 of its driving ratchet 94 which is journaled on a post 93 fixed on part 19 of the bracket. Ratchet 94 is adapted to be actuated from the universal bar of the machine by a pawl, not shown. The front sheet metal cover plate 95 of the machine is held to the comb 25 and bracket arms 27 by screws 96 and 97, as in the Corona machine, said cover plate having flat end portions 95^a clamped down on the horizontal portions of arms 27 by screws 97 threaded in holes 98 and serving in the present construction to clamp the hooked upper end of coil spring 84 in place on the left hand one of said bracket arms 27.
- 55 The operation of the tabulating mechanism is as follows:
- 60 The typist affixes as many of the removable and adjustable stops 66 as desired upon the stop bar 63, positioning them in notches in the bar corresponding with the desired column points of arrest of the carriage. The depression of the tabulator key rocks sub-lever 74 through the medium of draw link 78 in a direction causing finger 99 of the sub-lever to rock the upstanding arm of bell-crank lever 44 rearward simultaneously with the oblique rearward and downward move-
- 65 ment of counterstop 67 toward the tabulator stop bar 63 by reason of the pivotal connection of the counterstop with the inner end of the sub-lever. The counterstop and escapement releasing bell crank lever assume the positions shown in Fig. 4 at the end of the downward movement of the tabulator key, in which positions nose 69 of stop 67 has been interposed in the path of those abutment portions of stops 66 which extend down in front of stop bar 63, and releasing bell-crank 44 has rocked dog rocker 35 to its abnormally depressed position in which both of the escapement dogs 39 and 40 are below
- 70 and disengaged from the escapement wheel, thus freeing the carriage for a continuous running or jump movement which is arrested by the engagement with the set counter stop 67 of that one of the traveling column stops 66 located next to the right of the
- 75 80 85 90 95 100 105 110 115 120 125 130

counterstop at the time the tabulator key was depressed. Upon release of the tabulator key, the key actuated parts return to normal position under the influence of springs 84, 5 55 and 51 and the carriage is restored to the control of the escapement with dog 40 engaged with escapement wheel 41. The carriage may be jumped progressively from column zone to column zone by repeated actuation of the tabulator key.

Link 78 is disposed, as shown, so that it swings up and down about its pivotal connection with the tabulator key lever in case changing movements of the carriage shift frame an extent which carries its rear end between points equal distances above and below an oblique plane perpendicular to the path of case-shift movement of the shift frame and passing through the pivoted point 15 of the link on key lever arm 79, so that the counter stop 67 and releasing bell-crank 44 will be actuated uniformly by the tabulator key in both case shift positions of the platen carriage.

25 What we claim is:

1. In a typewriting machine, a main frame, a shift frame, a traveling platen carriage on the shift frame, escapement mechanism on the shift frame controlling travel of the carriage for letter spacing, key-operated means on the main frame for shifting the shift frame upwardly to change case, a tabulator key lever fulcrumed on the main frame adjacent one side of the machine and having an upstanding arm movable forwardly when its key is depressed, a sub-lever pivoted between its ends on the shift frame to swing about an up and down extending axis and extending transversely of the machine, a fore and aft extending link connecting the outer arm of said sub-lever with said upstanding arm of the tabulator key lever, a tabulator stop bar mounted on the carriage and extending parallel with the path of travel of the carriage at the rear of the shift frame, column stops on said stop bar, a fore and aft extending and endwisely movable counterstop pivotally held at its forward end to the inner arm of said sub-lever with its rear column stop engaging end normally forward of the path of travel of the column stops, means coactive with said counterstop to the rear of its pivot for guiding the stop to move endwise into the path of the column stops when the key of the tabulator key lever is depressed, spring means for restoring the counterstop and its actuating means, and an escapement releasing lever on the shift frame having an arm in the path of rearward movement of and operable by the inner arm of the sub-lever.

2. In a typewriting machine, a main frame, a shift frame, a platen carriage on the shift frame, a carriage escapement and a releasing device therefor on the shift frame,

tabulator stops on the carriage, key-operated means on the main frame for shifting the shift frame, a tabulator key lever on the main frame, a counterstop on the shift frame normally out of the path of travel of the tabulator stops on the carriage, a sub-lever pivotally supported intermediate its ends on the shift frame and having one arm for concomitantly actuating said escapement releasing device and setting said counterstop in the path of the tabulator stops on the carriage, and a link connecting the other arm of the sub-lever with the tabulator key lever to uniformly move said releasing device and uniformly set the counterstop in all case positions of the shift frame when the tabulator key lever is actuated.

3. A typewriting machine as claimed in claim 2, wherein the counterstop is pivotally connected at one end to the sub-lever and passes loosely through a guide on the shift frame between its pivot and its opposite end which is projectible into the path of the tabulator stops on the carriage.

4. A typewriting machine as claimed in claim 2, wherein cooperating abutments are provided on the counterstop and shift frame for limiting the setting movement of the counter stop.

5. A typewriting machine as claimed in claim 2, wherein means are provided on the main frame and key lever for limiting the throw of the lever in both directions, and means are provided on the counterstop and shift frame for determining the projected or set position of the counterstop, and the link connecting the tabulator key lever and sub-lever is permanently bendable to vary the distance between its ends.

6. In a typewriting machine, a sheet metal carriage bed having upstanding raceway flanges, a platen carriage on the bed having pendent raceway flanges, antifriction bearings in the raceways formed by the cooperating pairs of carriage and bed flanges, tabulator stops supported from the carriage in rear of the rear pair of carriage and bed flanges, a counterstop slidably extending through a guide slot in the rear bed flange below the lower edge of the rear carriage flange and the path of the bearings confined between said flanges, a lever pivotally held between its ends to the bottom of the carriage bed to rock transversely of the bed and having its inner arm pivotally connected with the forward end of the counterstop, tabulator-key operated means connected with the outer arm of said lever for rocking the same to project the rear end of the counterstop into the path of travel of the tabulator stops upon depression of the tabulator key, escapement mechanism for the carriage, and means operable by said sub-lever concomitantly with the setting of the counter-

stop to release the carriage from control of the escapement mechanism.

7. A typewriting machine as claimed in claim 6, wherein the counterstop is provided with an abutment portion engageable with the front face of the rear bed flange to arrest setting projection of the stop.

8. In a typewriting machine, a traveling platen carriage, a support therefor, an escapement therefor including a dog rocker, tabulator stops on the carriage, a counterstop on the carriage support, a lever pivoted intermediate its ends on the carriage support and having one arm connected with the counterstop for setting said stop in the path of the tabulator stops and retracting the counterstop, key operated means connected with the other arm of said lever for actuating the same, means coactive with the counterstop for determining its set position, and a second lever pivoted on the carriage support having an arm engageable with the dog rocker to rock the same to a position freeing the carriage from control of the escapement and an arm movable by a contact finger on an arm of the stop setting lever which is permanently bendable to vary the action of the stop setting lever on the dog rocker actuating lever.

30 In testimony whereof we hereunto affix our signatures.

ALONZO B. ELY.
EDWIN L. HARMON.
